UNITED STATES PATENT OFFICE.

HANS C. HANSEN, OF NEWTON, MASSACHUSETTS.

RULE AND LEAD CUTTER.

1,114,754.

Specification of Letters Patent.

Patented Oct. 27, 1914.

Application filed February 20, 1914. Serial No. 820,058.

To all whom it may concern:

Be it known that I, HANS C. HANSEN, a citizen of the United States, and resident of Newton, county of Middlesex, State of Massachusetts, have invented an Improvement in Rule and Lead Cutters, of which the following description, in connection with the accompanying drawing, is a specification, like characters on the drawing representing like parts.

This invention has reference to a machine for cutting strips of metal or other material into desired lengths and is designed primarily for use in cutting brass rules, leads and slugs of various thicknesses such as employed in printing.

Thin materials such as rules, leads, etc., are curved by the action of a cutter if the shearing blades operate at an angle, whereas if the shearing edges of the blades are substantially parallel for cutting such materials, the severed pieces are flat. Thick materials, however, such as slugs are much more easily cut if the shearing edges are angularly positioned. Accordingly, my present invention aims to provide an improved cutter in which the blades may be adjusted to the most efficient angle for the particular material to be cut.

Another object is to provide such a machine which will properly support the material to be cut regardless of the length and will insure the pieces being cut to the desired length with precision and accuracy.

Another object is to provide means whereby pieces of the same length as a given sample piece may be cut off without the trouble of measuring the sample.

Another object is to provide a device in which the parts shall be strong and durable and arranged to secure the cutting of heavy and thick pieces as well as light and thin pieces with the application of comparatively small power.

Another object is to provide a construction in which the cutting action is opposed by spring pressure acting to restore the shearing blades to open position, and in which the means for adjusting the shearing blades to the required angle is also opposed by spring pressure, and in which in the preferred form a single spring secures both of these functions.

These and other objects of the invention will appear more fully from the following description and accompanying drawings,

and the novel features will be particularly pointed out in the claims.

The drawings illustrate a preferred form of machine embodying my invention, and suitable for use as a printer's rule, lead and slug cutter.

In the drawings, Figure 1 is a plan view of the machine; Fig. 2 is a rear elevation of the same; Fig. 3 is a sectional view taken on the line 3—3, Fig. 2; Fig. 4 is a sectional view taken on the line 4—4, Fig. 1; Fig. 5 is a sectional view taken on the line 5—5, Fig. 3; Fig. 6 is a sectional view taken on the line 6—6, Fig. 2, showing the parts in position for cutting thin material; and Fig. 7 is a sectional view similar to Fig. 6 but showing the parts adjusted for cutting thick materials.

Referring to the drawings in detail, 1 designates a base consisting preferably of a casting presenting a bed or material support 2, and having legs 3, 4 and 5. The cutting mechanism comprises a fixed blade 6 secured to the bed plate and a movable coöperating 80 blade 7 carried by a C-shaped arm 8.

The bed or material support is shown as extending to one side of the fixed blade and is provided with a shoulder 9, thus forming a guideway for the strip of material. The 85 surface of the bed above this shoulder is graduated to any desired scale as indicated at 10 and may conveniently be marked to designate ems, thus providing convenient means for cutting strips of desired length. 90

The two shearing blades broadly considered are supported in blade carrying members, the lower one by that portion of the bed plate to which it is immediately fastened and the upper one by that portion of the C- 95 shaped arm to which it is immediately fastened, and any convenient means may be provided to adjust the relative angular position of these blade carrying members. In the machine illustrated this result is secured by 100 forming the blade carrying member of the upper shearing blade integral with the C-shaped arm 8 and rendering that arm relatively adjustable to the lower blade carrying member by means of an adjustable auxiliary support 11 in such a manner as to raise or lower the pivot of the C-shaped arm, but the invention broadly considered is not restricted to this construction, which is here presented as the preferred form. The auxiliary support may conveniently be pivoted to the base as at 12 and controlled by means 105 110

of an eccentric 13 rotatably mounted in the frame and operating in a hole 14 in the auxiliary support.

The position of the eccentric is controlled by a handle 15 pivoted in a slot in one end of the eccentric and having a pin 16 adapted to project into any one of a series of holes 17 in a plate 18 secured in the frame. A spring 19 operates to press this lever toward the plate. I thus provide means whereby the shearing edges of the blade may be adjusted to lie substantially parallel as they approach each other for cutting thin strips such as rules or leads, or by a simple adjustment of the handle 15 the pivot of the arm 8 may be raised to such an extent that the upper blade will approach the lower blade at a considerable angle as indicated most clearly in Fig. 7. By this means thin pieces may be cut without bending or curving the same and thick pieces may be cut by the more powerful and efficient diagonal stroke.

The arm 8 is curved to extend under the support and is connected at the lower end to an operating lever 20 thus leaving the top of the machine free and providing convenient access to the material support and shearing blades. The operating lever is pivoted to the frame as indicated at 21 and may be connected to the arm 8 by any convenient means. In the form shown sockets 22 and 23 are provided in the lever and in the end of the arm, respectively, to receive the ends of a compression link 24. The link is of substantially the shape of a dumbbell in longitudinal section and its width is equal to the thickness of the lever 20 and arm 8 so that the action of the lever will give the arm a movement about its pivot without causing any lateral strain thereon. The operating lever and link thus have no tendency to throw the blades out of alinement. The sockets may be conveniently of such a shape as to permit the insertion of the link laterally but prevent its withdrawal longitudinally, and the socket 22 in the lever is so positioned that the projecting boss 25 will prevent accidental removal of the link laterally. The link can easily be removed when desired by first removing the pivot pin 21 of the lever 20. The downward movement of the lever is limited by a stop 26 and its upward movement is limited by engagement with the base as indicated at 27. A coiled spring 28 connected to the arm 8 at 29 and to the auxiliary support at 30 returns the arm to initial position after the cutting operation, and has the additional function of urging the auxiliary support upwardly about its pivot. The spring thus holds the auxiliary support against the eccentric at all times, the eccentric and spring at all times acting in opposition to each other. The rotation of the eccentric thus causes the desired adjustment of the auxiliary support.

Upon operation of the device such strain as is exerted upon the pivot of the arm 8 is in an upward direction and this is resisted by the eccentric so that the auxiliary support is positively held in position. This construction makes it possible to employ an eccentric pin of simple and cheap construction. The pin shown consists of a cylindrical shaft having its central part turned down to present a reduced portion of sufficient eccentricity to provide the desired adjustment. It is to be noted that there is a distinct shoulder at each end of the central eccentric portion extending entirely around the pin as clearly indicated in Figs. 6 and 7, that is, the central and outer portions are not tangent to the same plane at any point. The auxiliary support when positioned against the central portion will therefore always lie between these shoulders and prevent longitudinal movement of the pin. This pin may be inserted by so positioning the auxiliary support that the holes in the base and in the auxiliary support are in alinement. The spring 28 holds the auxiliary support against the reduced eccentric portion of the pin and between the shoulders thereof thus holding the pin against longitudinal displacement. This spring is preferably positioned in a recess 31 in the arm thus being concealed, whereby a neat appearance is presented.

An adjustable gage 32 is provided presenting a stop to facilitate cutting pieces of any desired length and this gage is preferably attachable at either side of the shearing blades. The gage may thus be used in the position shown for cutting either long or short pieces or may be shifted to the opposite side for more conveniently cutting a number of short pieces. The gage shown is adjustably held in position by a gage clamp 33 which may be attached to either of two similar square clamp-receiving extensions 34 and 35 formed on the base. I provide adjustable stops 36 and 37 to determine the position of the clamp upon the base, each stop consisting of a depending lug and a set screw mounted therein. The clamp shown comprises a block having a square hole 38 to fit either square extension, and a second hole 39 to receive the gage 32. A thumb screw 40 secures the clamp in position. Clamping means is provided to grip the scale and hold it in adjusted position in the clamp. The clamping means illustrated consists of a spring pressed detent 41 and an eccentric 42 rotatably mounted in the clamp and operable to retract the detent against the pressure of its spring. The eccentric is provided with an arm 43 for convenient operation. The scale is preferably provided with a series of notches 44 into which the end of the spring pressed detent may project, these notches being placed to correspond with the graduations 130

tions 10 to facilitate setting the scale in the exact position desired.

I have illustrated a convenient means whereby one or more pieces may be cut to size to correspond with a given sample without the necessity of measuring such sample. A shoulder 45 upon the scale near one end is so positioned that when the clamp is positioned, as shown, the distance 10 between this shoulder and the opposed face of the clamp will be equal to the distance between the opposite end of the scale and the shearing edges of the blades. The sample may be placed between the shoulder and the 15 clamp thus accurately determining the desired position of the scale. A thumb screw 46 is provided to hold the scale in adjusted position when thus cutting to sample. The pieces cut off between the end of the scale 20 and the shearing blades will then be of the same size as the sample. By this means the trouble of measuring the sample and consequent sources of error are eliminated.

I have illustrated a device in which the material support and lower shearing blade are fixed in position and an upper blade is adjustable and movable relative thereto to sever the material. The essential feature, however, is that relative adjustment and relative 30 cutting movement should be provided, and this may be accomplished in a variety of equivalent ways within the scope of my invention.

I have illustrated a preferred form of 35 scale but it will be obvious to one skilled in the art that various modifications may be made in the type of scale to be used.

Having fully described my invention, what I claim as new and desire to secure 40 by Letters Patent is:

1. A cutter comprising a material support, a shearing blade connected thereto, a coöperating shearing blade, a pivoted arm carrying said coöperating shearing blade 45 and means to vary the relative position of the material support and the pivot of said arm whereby the angle between the cutting edges of the shearing blades may be varied.

2. A cutter comprising a lower fixed 50 shearing blade, a support extending transversely to and at one side of said shearing blade and presenting a guideway, an adjustable auxiliary support, an upper blade, a lever carrying said upper blade and pivoted 55 to said auxiliary support whereby the angle between the shearing blades may be varied by adjusting the auxiliary support, and means to operate said lever to sever the material.

60 3. A cutter comprising a base presenting a material support, an adjustable support pivoted thereto, an arm pivoted to said adjustable support, coöperating shearing blades secured to the base and pivoted arm 65 respectively, eccentric means for adjusting

said adjustable support and holding it in adjusted position whereby the position of the pivot of said arm may be varied relative to the material support to thereby vary the angle between the cutting edges of said 70 blades and means to operate the pivoted arm.

4. A cutter comprising a lower fixed blade, a main support extending transversely to and at one side of said blade, 75 an auxiliary support pivotally connected to said support and adjustable relatively thereto, an upper movable blade, an arm carrying said upper blade pivotally connected to said auxiliary support and extending beneath the main support, an operating lever pivoted to the main support, and a connection between said arm and operating lever consisting of a compression link having rounded ends fitting into sockets in the arm 80 and lever, respectively.

5. A cutter comprising a lower fixed blade, a material support extending transversely to and at one side of said blade, an upper movable blade, a C-shaped arm carrying 90 said upper blade and pivotally connected to and extending beneath the support, an operating lever pivoted to the support and a connection between said arm and operating lever beneath the material support consisting 95 of a compression link having rounded ends fitting into sockets in the arm and lever, respectively.

6. A cutter comprising a base presenting a material support, shearing blades operable 100 to sever the material resting on said material support, said base being provided with gage clamp receiving means at both sides of the shearing blades, a gage, and a gage clamp attachable to either of said gage 105 clamp receiving means to hold the gage in adjusted position relative to the material support, and on either side of the shearing blades.

7. A cutter comprising a base presenting 110 a material support, shearing blades operable to sever the material resting on said material support, said base being provided with gage clamp receiving means at both sides of the shearing blades, a gage, a gage clamp attachable to either of said gage clamp receiving means to hold the gage in adjusted position relative to the material support, and adjustable means to determine the position of the gage clamp when applied to one of said 115 gage clamp receiving means.

8. A cutter comprising a lower fixed shearing blade, a main support extending transversely to and at one side of said shearing blade and presenting a guideway, an auxiliary support adjustably connected to the main support, an upper shearing blade, a C-shaped lever carrying said upper shearing blade and pivoted to the auxiliary support and extending beneath the guideway, 125 130

means connected with said lever beneath the guideway to operate said lever to bring the shearing blade into operation to sever the material.

5. 9. A cutter comprising a fixed shearing blade, a material support presenting a guideway extending transversely of and to one side of said fixed blade, a gage clamp secured to the material support, a gage adjustable in said gage clamp and extending longitudinally of the material support, said gage having a shoulder so positioned that the space between the shoulder and the opposed face of the clamp will always be equal 10 to the space between the end of the gage and the cutting edge of the fixed shearing blade whereby sample pieces may be placed between said shoulder and the face of the gage to determine the position of the gage when 15 it is desired to cut other pieces of the same size as the sample piece, a movable shearing blade, an arm carrying said movable blade, and means for operating said arm to sever the material.
- 20 10. A cutter comprising a material support, a shearing blade connected thereto, a coöperating shearing blade, a blade carrying member to which said coöperating blade is secured, said blade carrying member being adjustable to vary the relative angular position 25 in which the coöperating blade approaches the fixed blade, and operating means for said blade carrying member.
- 30 11. A cutter comprising a lower fixed blade, a main support extending transversely to the blade, an auxiliary support adjustably connected to said main support, an upper movable blade, an arm carrying said upper blade movably connected to said 35 auxiliary support and extending beneath the main support, a lever fulcrumed on the main support and operatively connected to said arm below the main support to exert its line of thrust on said arm in substantially the 40 direction of movement of the upper blade.
- 45 12. A cutter comprising a base presenting

a material support, an adjustable support pivoted thereto, an arm pivoted to said adjustable support, coöperating shearing blades secured to the base and pivoted arm 50 respectively, a spring engaging said adjustable support and pivoted arm and coöperating therewith to urge the adjustable support to elevated position and the arm to initial position, and means operating in opposition to the spring to hold the adjustable support in adjusted position.

55 13. A cutter comprising a base presenting a material support, an adjustable support pivoted thereto, a C-shaped arm pivoted intermediate its ends to said adjustable support, spring means coöperating with said adjustable support and C-shaped arms to urge the adjustable support to elevated position and the C-shaped arms to initial position, coöperating shearing blades secured to the base and to one end of the C-shaped arm, respectively, and operating means engaging the other end of said C-shaped arm, adjusting means acting in opposition to the 60 spring means for controlling the position of the adjustable support.

65 14. A cutter comprising a base presenting a material support, a fixed shearing blade connected to said material support, a C-shaped arm pivotally connected to said base intermediate its ends, a movable shearing blade secured to one end of said C-shaped arm and coöperating with said fixed shearing blade, operating means connected to the 70 other end of said C-shaped arm and acting thereupon substantially in the direction of movement of said movable blade whereby comparatively little strain is put upon the pivot of said arm.

75 In testimony whereof, I have signed my name to this specification, in the presence of two subscribing witnesses.

HANS C. HANSEN.
